UNITED STATES PATENT OFFICE.

GODFRAY EBEL, OF RUSSELL, KANSAS.

DESIGN FOR A LAMP-STOVE.

SPECIFICATION forming part of Design No. 33,801, dated December 25, 1900.

Application filed August 10, 1900. Serial No. 26,533. Term of patent 7 years.

To all whom it may concern:

Be it known that I, GODFRAY EBEL, a citizen of the United States, residing at Russell, Russell county, Kansas, have invented and 5 produced a new and original Design for Lamp-Stoves, of which the following is a specification.

My invention relates to lamp-stoves; and 10 my object is to produce a new and original design for the same which is both ornamental and useful.

In the accompanying drawing, which illustrates the design in perspective, the leading or material features of the design reside in a 15 vertical cylindrical figure, in a series of holes near the upper end of said figure, in a top plate provided with holes, and in a curved window near the lower end of the figure.

Minor features of the design reside in the 20 vertical plates or strips at opposite sides of and projecting above the window and in the curved door between said plates, in the knob or handle projecting from said door, in the outwardly-projecting lug or pin below the 25 window, and in pins projecting upwardly from the top plate.

Referring to the drawing in detail, 1 designates the vertical cylindrical figure.

2 designates the curved window.

3 designates the curved door.

4 designates the knob or handle for the door.

5 designates the vertical plates at opposite sides of the window and door.

6 designates the openings in the upper part 35 of the figure.

7 designates the top plate.

8 designates the openings in the top plate.

9 designates the outwardly-projecting pin or lug below the window.

10 designates the lugs or pins projecting 40 upwardly from the top plate.

What I claim as new, and desire to secure by Letters Patent, is—

The design for a lamp-stove herein shown 45 and described.

In testimony whereof I affix my signature in the presence of two witnesses.

GODFRAY EBEL.
